Primary Examiner—Joel Sincavage*Assistant Examiner*—Cynthia E. Ramirez*Attorney, Agent, or Firm*—John D. Gugliotta**[57]****CLAIM**

The ornamental design for a shoe attached cleaning implement, as shown and described.

DESCRIPTION

FIG. 1 is a front, left and bottom perspective view of a shoe attached cleaning implement showing my new design, the broken lines showing a golf shoe attached thereto. For illustrative purposes only and forming no part of the claimed design;

FIG. 2 is a front elevational view thereof;

FIG. 3 is a side elevational view, the other side being a mirror image thereof; and,

FIG. 4 is a bottom plan view thereof.
